UNITED STATES PATENT OFFICE.

GEORGE W. LAWBAUGH, OF GENESEO, ILLINOIS.

FORCE-PUMP.

SPECIFICATION forming part of Letters Patent No. 237,295, dated February 1, 1881.
Application filed November 8, 1880. (No model.)

To all whom it may concern:

Be it known that I, GEO. W. LAWBAUGH, of Geneseo, in the county of Henry, and in the State of Illinois, have invented certain new and useful Improvements in Force-Pumps; and I do hereby declare that the following is a full, clear, and exact description thereof, reference being had to the accompanying drawings, making a part of this specification, in 10 which—

Figure 1 is a perspective view of my pump and pump-stock separated from each other. Fig. 2 is a like view of the same as combined for use, and Fig. 3 is a vertical central section 15 of said parts.

Letters of like name and kind refer to like parts in each of the figures.

The design of my invention is to simplify the construction and to increase the efficiency 20 of force-pumps; and to this end it consists in the means employed for forming a tight joint between the pump cylinder and stock, substantially as and for the purpose hereinafter specified.

25 In the annexed drawings, A represents the cylinder of my pump, having an open upper end, and having its lower end formed upon an angle of about forty-five degrees from a vertical line, and inclosed by means of a plate, B, 30 that at its center is provided with a semi-spherical perforated portion, b, above which is placed a flap-valve, C, of usual form, that is arranged to open upward.

Immediately above the lower end of the cylinder A is a lateral branch, A', which has a 35 vertical outer end, and within the same is provided with a groove, a, that forms two concentric circular V-shaped edges, a', as seen in Figs. 1 and 3.

40 Within the inner end of the branch A' is provided a flap-valve and seat, D, which have a downward and an outward inclination from the interior of the cylinder A, said valve being arranged to open outward.

45 A plunger, E, of ordinary construction, is fitted within the cylinder A, and when caused to reciprocate by means of a plunger-rod, F, will cause water to be drawn inward through

the lower valved end of said cylinder, and to be expelled therefrom through the branch A'. 50

The cylinder A is secured to or upon a pump-stock, G, by means of straps H and H, one of which passes around each end of said cylinder and around the contiguous portion of said pump-stock. The open end of the branch A' bears against the pump-stock G, and incloses an opening, g, which communicates with the interior of the latter. A water-tight joint is produced between the end of said branch and said pump-stock by means of the V-shaped edges a', which cut into the wood, and by means of an annular gasket, I, of rubber or other yielding material, which is placed within the groove a between said concentric edges. 65

From the upper portion of the pump-stock G the usual discharge pipe or spout g' extends outward and then downward, and in order that a flexible hose, K, may be connected therewith and extended horizontally outward without breakage, an elbow, k, is attached to the end of said hose, and is adapted to be passed over the end of said spout, and to be connected therewith by means of locking-lugs similar to those employed for hose-coupling. As thus 70 arranged the hose can be extended outward from the pump with perfect safety, as it will not be bent by such operation. 75

It will be seen that the seat of the outlet-valve has such inclination as to cause its upper end to project into the cylinder, while the seat of the inlet-valve has an inclination which causes it to approach the plane of the former. This construction lessens the dead-water space within the cylinder and correspondingly reduces the friction and loss of power caused by such dead water, it being true that much power is required to overcome the inertia of such water, and its stoppage, when the plunger or piston changes its direction, is the occasion of a further loss of power, the waste corresponding to the amount of dead water contained within the cylinder. 80 85 90 95

The means employed for connecting a flexible hose to or with the discharge-spout is not claimed herein, it being my intention to make

such improvement the subject of a separate patent.

Having thus fully set forth the nature and merits of my invention, what I claim as new,
5 is—

As a means for forming a joint between the cylinder A and pump-stock G, the concentric V-shaped edges a' , separated by the groove a , which contains the flexible gasket

I, substantially as and for the purpose specified.

In testimony that I claim the foregoing I have hereunto set my hand this 3d day of November, 1880.

GEO. W. LAWBAUGH.
